FACE MASK FOR ANESTHESIA

Frank L. Mayer, Denver, Colo., assignor to J. J. Monaghan Company, Inc., Denver, Colo., a corporation of Colorado

Filed Oct. 30, 1958, Ser. No. 53,226

Term of patent 14 years

(Cl. D83—1)

I claim:

The ornamental design for a face mask for anesthesia, as shown.
